UNITED STATES PATENT OFFICE.

NORMAN MARSHALL, OF NEWTON, MASSACHUSETTS.

MANUFACTURE OF RIVETS.

No. 820,586.

Specification of Letters Patent.

Patented May 15, 1906.

Application filed October 28, 1903. Serial No. 178,459.

To all whom it may concern:

Be it known that I, NORMAN MARSHALL, of Newton, in the county of Middlesex and State of Massachusetts, have invented certain new and useful Improvements in Manufacture of Rivets, of which the following is a specification.

The invention relates to the manufacture of rivets on metal plates; and its object is to provide rivets which may be economically made and by which other parts may be effectively and conveniently riveted to the metal plates. The invention may be used with especial advantage in riveting together small parts made from sheet metal—such, for instance, as various parts of incandescent-lamp sockets and other small electrical appliances, although not confined to such use.

Heretofore it has been customary to connect such parts with screws or by rivets passed through holes in the connected parts, as in the usual manner of riveting parts together. In practicing the present invention I form an integral rivet on one of the plates or parts to be connected together by causing a flow of the metal from one side of the plate toward and out from the opposite side of the plate and shaping the outflowing metal to give the rivet the desired form. The lateral flow of the metal at the point in the plate where the rivet is to be formed is produced by a die which is forced into the side of the plate opposite to that on which the rivet is to be formed, and the shape of the rivet is determined by an oppositely-arranged die into which the metal is forced. I have discovered that by properly shaping and proportioning the forcing or male die the metal of the plate may be caused to flow laterally into the shaping or female die without disrupting or separating the metal from the plate. The exact shape and the proportions of the male die requisite for the proper results will vary somewhat with the shape and size of the rivet to be produced and with the thickness and composition of the plate. The die should be so shaped and proportioned that the lateral and forward pressure exerted by the die on the metal will be distributed in such manner as to cause a forward flow of the metal as the die enters the plate and not pierce or disrupt the plate. To this end the sides of the die should converge to a blunt or rounded point, the inclination or curve of the sides and the shape of the point depending within narrow limits on the thickness and composition of

the plate and the size and shape of the rivet to be formed thereon.

The invention will be more fully understood from an explanation, in connection with the accompanying drawings, in which—

Figure 1 is a section through a plate on which a rivet has been formed in accordance with my invention. Fig. 2 is a plan view of the same. Fig. 3 is a sectional view showing the dies which I prefer to employ in practicing the invention, and Figs. 4, 5, and 6 are views of parts secured by rivets formed in accordance with my invention.

In Figs. 1, 2, and 3 a metallic plate A, of sheet metal, such as is used in the manufacture of the parts of electric-lamp sockets, switches, &c., is shown upon an enlarged scale the better to illustrate the present invention.

The plate A has formed thereon one or more integral rivets a, which, as shown, are cylindrical in shape. This integral rivet is formed by subjecting the plate to pressure between a male die B and a female die C. The female shaping-die C is cylindrical to correspond to the shape of the rivet, while the male forcing-die has a cone-like form with blunted or curved end b and curved converging sides b', substantially as indicated in Fig. 3.

I have found that a male die of substantially the form shown will cause a forward flow of the metal as the die enters the plate, so that the metal is upset from the opposite side of the plate. As this metal is forced forward and out from the side of the plate by the male die it enters the female die and assumes the shape of such die, thus forming the rivet. Integral rivets may thus be quickly and cheaply formed which will form a more secure and efficient connection for other parts than independent rivets. The use of such rivets also facilitates the assembling of the parts, reduces the number of parts to be handled and the operations to be performed, with a resulting reduction in the cost of manufacture.

In the manufacture of small parts, such as used in electric-lighting fixtures, the invention is especially valuable, and its application to some of such devices is shown in Figs. 4, 5, and 6. In Fig. 4 the rivet a' is formed on a sheet-metal piece A' and is used in connecting the piece D thereto, the parts forming a contact for Westinghouse lamps. In Fig. 5 the rivet a'' is formed on a strip A'' and connects a switch-contact E thereto. In Fig. 6

two rivets *a* are formed on a piece *A*, which forms the frame for a socket-key *F*, and these rivets secure the spring contact-strip *G* to the frame.

5 If it is desired to form a rivet with a flat upper end, this may be done by mounting a plunger *C* in the female die, which bears upon the metal as it is upset and tends to keep it flat at the end.

10 I prefer to provide the male die with a shoulder *B'* for limiting the entrance of the die into the plate *A* and also to press on the plate about the cavity formed by the die *B* and prevent any distortion of the plate at

15 this point.

What I claim, and desire to secure by Letters Patent, is—

1. A metal plate provided with an integral

imperforate cylindrical rivet on one side and a conical-shaped recess on the opposite side ²⁰ from which the metal has flowed to form the rivet, substantially as described.

2. A metal plate provided with an integral imperforate rivet on one side and a recess on the opposite side, the cross-sectional area of ²⁵ which gradually increases from the surface of the plate toward the rivet and from which the metal has been forced outwardly and laterally to form the rivet, substantially as described.

In testimony whereof I have affixed my signature in presence of two witnesses.

NORMAN MARSHALL.
